STACKED JACK GAME PUZZLE

William H. Baynes, Los Angeles, Calif.
(4122 Greenbush Ave., Sherman Oaks, Calif. 91403)

Filed Feb. 27, 1974, Ser. No. 446,526

Term of patent 14 years

Int. Cl. D21—01

U.S. Cl. D34—15 M

FIG. 1 is a perspective view of my new design for a stacked jack game puzzle;

FIG. 2 is an enlarged side elevational view thereof;

FIG. 3 is a top plan view thereof; and

FIG. 4 is a bottom plan view thereof.

I claim:

The ornamental design for a stacked jack game puzzle, substantially as shown and described.
